Houston, Tex.

Application May 15, 1936, Serial No. 79,996

2 Claims. (Cl. 255—35)

This invention relates generally to apparatus for connecting and separating threaded sections of pipe and the like.

In the drilling of a deep well it is customary to use a drill stem comprising a pipe made up of sections threaded together. As the drill bit on the lower end of the drill stem penetrates and descends into the earth it is necessary to lengthen the drill stem, and this is done by adding threaded sections of pipe to the upper end of the drill stem. It is frequently necessary to withdraw the drill stem from the well and when the drill stem is withdrawn the sections of the pipe are disconnected as they are elevated above the derrick floor. Various tongs have heretofore been devised for connecting the sections of pipe together as the drill stem is lowered into the earth, and also for disconnecting the sections of pipe as the drill stem is withdrawn from the earth, and these tongs are generally known as "make-up" and "break-out" tongs.

In the past it has been the general practice to allow the driller to rotate one pipe section with respect to the other at any speed which to him appeared proper. Some drillers employ excessive speeds, and this has resulted in "burning" the threads, thereby causing trouble well known to those skilled in the art.

One of the main objects of this invention is to provide a tong embodying means to cause it to automatically release the pipe when the driller allows the pipe to be rotated at a speed greater than that at which the pipe may be rotated without injuring the threads, and to automatically re-grip the pipe when the speed of rotation is lowered the proper amount.

Conventional "make-up" and "break-out" equipment includes a rotary used during drilling operations to rotate the drill and which during "make-up" and "break-out" operations is used to rotate that portion of the drill stem below the uppermost section; slips to hold the drill stem against downward vertical movement in the rotary; a tong substantially stationarily supported by the derrick; and another tong carried by the rotary so that when the rotary is rotated one tong serves to hold the uppermost section of the pipe stationary, and the other tong serves to rotate the lower section with the rotary, the rotation of the sections with respect to each other affecting either the engagement or disengagement of the threaded ends thereof.

If the pipe should move downwardly more than a predetermined distance with respect to the tong supporting means, damage results either to the

tong and its support or both. Another important object of this invention is the provision of safety means in the tong construction so that no damage is suffered by the tongs or associated driving means when there is excessive vertical movement of the pipe with respect to the tong due to the failure of the slips or other causes.

Trouble has also been experienced with present tools in that they are not adaptable to all types of rotaries and general conditions found in the oil field. The present tools are also found lacking in conveniences and safety devices. This invention has as an added object, the provision of means to supply the need therefor.

In the drawings Fig. 1 is a fragmentary elevation showing the preferred embodiment of the invention applied to the conventional drill stem and rotary; Fig. 2 is a fragmentary elevation similar to Fig. 1, with certain parts in section, and showing a modified form of the tong supporting means; Fig. 3 is a section along the line 3—3 of Fig. 2; Fig. 4 is a section along the line 4—4 of Fig. 2; Fig. 5 is a section along the line 5—5 of Fig. 1; Fig. 6 is similar to Fig. 5 with some parts of the tongs in section; Fig. 7 is a section of the stop means used in yieldably holding the tong when swung away from the pipe; Fig. 8 is a section of the pin placed in the end of the tong handle to prevent the same from passing through the head unless such is desired; and Fig. 9 is a view showing how the toggle linkage is joined to the wrench body.

In Fig. 1 the pipe is indicated at 1 having an upper section 1a and a lower section 1b. Slips are indicated at 2 supporting the pipes in the rotary 3. The telescopic post 4 has an inner section 5 and an outer section 6, the inner section 5 being carried by the adapter 7. The adapter 7 is joined to the inner section 5 by means of the pin 8, and fits in the hole 9 of the rotary 3. It is prevented from rotating by the arm 10. The pin 11 in the outer section 6 extends into the groove 12 of the inner section and allows vertical movement of the outer section with respect to the inner section, but not rotational movement. The upper end of the outer section 6 terminates in the cap 13 which is welded thereto at 14. The outer section 6 is supported by the spring 15 which bears against the cap 13, and the inner section 5. Mounted on the cap 13 by means of balls 16 is a rotatable head having two sections, 17a and 17b being pivotally connected together at 18. The balls 16 are inserted through the hole 19, such hole being sealed by the screw plug 20. The upper section 17a has on its under side a shoulder 55

21 so positioned as to rest on the adjustment screw 22 found in the lower section 17b. The upper section 17a is substantially a hollow box (see Fig. 2) having rectangular holes 23 in its 5 end sections for the reception of the wrench handle 25. Within said head are found two sets of rollers 26 and 27, the diagonally spaced ones being of the same shape. Rollers 27 are made 10 square to present flat surfaces giving more bearing area to the wrench handle 25 in order that continued use of the wrench will not cause the handle to become indented along its length. The rollers 26 and 27 (see Fig. 4) are rotatively and 15 removably held in place on screw pins 28. The rollers 27 being square present four separate wearing surfaces, thereby seldom, if ever, needing replacement. The rollers 26 normally do not touch the handle and become active only when the wrench is picked up on its inner end to be 20 moved in or out of the head 17a.

To permit separation of the gripping means 29 from the handle 25 in the event of excessive downward movement of the pipe 1 because of the failure of the slips 2, or for any other cause, the 25 invention provides shearing means which will now be described. The gripping means includes an actuator member 46 which is made in the form of a yoke having arms 36 and 37 for the reception of the inner end of the handle 25 (Fig. 5). The inner end of the handle 25 has a downwardly opening slot 31 (Fig. 2) for the reception of the square bushing 43 on permanent pin 42, which pin 42 extends through and is connected to the arms 36 and 37 of the yoke of actuator 46. Extending above the parts just referred to and connecting the arms 36 and 37 of the yoke is a frangible pin 41, and the handle 25 is provided with upwardly extending lugs 32 and 33 having holes 34 and 35 through which said pin 41 40 extends to normally hold the handle 25 in alignment with the actuator 46.

The lower holes 40 receive the frangible pin 41 when the pipe gripping means 29 is inverted with respect to the handle 25. This permits universal 45 use of both the handle and the pipe gripping means.

The permanent pin 42 serves to transmit all 50 torsional loads from the handle 25 to the gripping means 29.

If the pipe 1 should drop down an excessive 55 distance with respect to the rotary 3 the shear pin 41 first fails. This allows the permanent pin 42, and its square bushing 43, to slip out of the slot 31, thus permitting separation of pipe gripping means 29 from the handle 25 and preventing damage that would otherwise occur.

The pipe-gripping means illustrated in Figs. 5 and 6 has a main body or jaw portion 44. Pivoted to this body at 45 is the actuating member 46 having connected to it at 47 a chain 48 which passes around the pipe 1 and back to the body. The chain 48 is connected to the handle 49 of the toggle linkage by the short link 57 (Fig. 5).

To separate the tong or gripping means from the pipe the handle 49 of the toggle linkage is first pulled away from the head. This allows the end 55 (see Fig. 9) of the handle 49 to be lifted from the U-shaped cup 50, thus freeing the tong from the pipe.

70 As illustrated in Figs. 5 and 6, a force F (when the rotary is rotated) would be applied to the wrench handle by the head 17a in a clockwise direction. This causes rotation of the actuator member 46 about the pin 45. This results in a 75 tightening of chain 48 about the pipe 1, forcing

the jaws 51 firmly against the pipe. The rotation of the actuator member 46 about the pin 45 is yieldably resisted by the coil spring 52 acting against the pin 53. The pin 53 is connected to the body 44 through the side plates 54. 5

When the speed of rotation of the handle 25 in the direction of the force F becomes great enough, centrifugal force begins to act on the handle in such a way that it is shifted from the solid line position (see Fig. 6) to the dotted line 10 position. This moves the pin 47 in such a direction as to loosen the chain 48 from around the pipe thus allowing automatically the jaws 51 to become disengaged from the pipe 1.

Because of centrifugal force effecting the engagement of the jaws, it is impossible for the driller to rotate the pipe above the speed where the handle 25 starts to shift from the solid line position to the dotted line position.

It is customary to swing the tong out of the 20 way when a section of pipe is being raised or lowered. In Fig. 7 is illustrated a spring actuated stop pin 56 positioned so as to hold the lug 55, extending below the lower head member 17b, against the lug 56a on the cap 13. When the 25 tong is released from the pipe and swung out of the way, it is yieldably held until needed further.

In Figs. 1, 2 and 8 is illustrated a pin stop 64 placed in the end of the handle 25 to prevent inadvertent inward movement of said handle 30 through the head 17a. When it is desired to remove the handle inwardly from the head the pin 64 may be pressed inwardly against its spring to permit such movement.

In Fig. 2 a shear pin 58 is shown in place of 35 the spring 15 shown in Fig. 1. Should there be excessive downward movement of the pipe 1 with respect to the rotary table 3 due to the failure of the slips 2, or for any other reason, the shear pin 58 would first yield, allowing the outer 40 section 6 to drop down. If such downward movement of the pipe 1 was not checked before the outer section 6 strikes the adapter 7 then the frangible pin 41 would be broken allowing the pipe 45 gripping means 29 to become separated from the handle 25, thus preventing damage to either the post or tong.

In Fig. 1 a construction is illustrated in which 50 lubrication is needed for the telescopic sections. Grease is applied through the cup 61 to the space 62. The grease passes up through the hole 63 and over the cap 13 to lubricate the balls 16. The grease enclosed also serves as a cushion for the outer section 6 when moved suddenly downward with respect to the inner section 5. 55

In the use of the invention the sections of pipe 1a and 1b are to be joined or separated. Fig. 1 shows the apparatus so arranged as to be used to separate the two sections. The upper 60 section 1a is held stationary by the tong 59 which has its handle tied to a corner of the derrick (not shown) by the rope or cable 60. The lower section 1b is then rotated by revolving the table 3, (by means of conventional machinery 65 not shown), which supports the lower section 1b and all of the sections joined on below it, by means of the slips 2. The rotary movement of the rotary 3 is imparted to the lower section 1b through the post 4, handle 25 and pipe gripping 70 means 29. When the separation has been completed the tongs are loosened and swung out of the way. The upper section 1a is then placed over to one side of the derrick and the lower section 1b is elevated by suitable means (not 75

shown) until the threaded connection at its lower end (not shown) comes into position. This operation is repeated until all of the pipe sections are out of the hole.

5 It will be apparent that when the pipe sections are to be replaced in the hole that the operations are repeated but in reverse order, the tongs being turned thru 180 degrees.

10 It can readily be seen that a driller with little judgment might ruin an entire string of pipe while removing it from or inserting it in the well by simply rotating too fast; and as the pipe goes in and out of the hole many times during the drilling of a well, the danger of injuring the pipe 15 is continuously existent.

15 It frequently happens that slips 2, because of improper use, fail to support the pipe while the entire apparatus is joined together as illustrated in Fig. 2. If such happened and no safety 20 means were provided, damage would result to the tong, post or both. This would cause unnecessary expense in replacing the same, whereas the simple shearing means used in this invention prevents such damage and is very inexpensive to 25 replace.

Although this invention has been illustrated and described in connection with a preferred embodiment, modifications within the true spirit and scope of the same are intended to be covered 30 in the hereto appended claims.

It will be understood that the invention may be used with well casings and tubings as well as with drill pipe. As a matter of fact, it will be found particularly useful in preventing "burn-

ing" of the threads of casing sections by preventing an excessive relative speed of rotation thereof.

We claim:

1. A tong comprising a gripping element and a handle, a relatively strong connecting element between said gripping element and said handle for transmitting operating force in one plane from said handle to said gripping element, and relatively frangible connecting means between said gripping element and handle for normally preventing relative vertical movement of said gripping element and handle, said last means being frangible to permit relative vertical movement of said gripping element and handle when predetermined vertical forces are applied tending 10 to move said gripping element and handle relative to each other. 15

2. A tong comprising a gripping element and a handle, a relatively strong connecting element between said gripping element and said handle for transmitting operating force in one plane from said handle to said gripping element, and relatively frangible connecting means between said gripping element and said handle for normally preventing relative movement of said gripping element and said handle in a different plane from said first mentioned plane, said last means being frangible to permit relative movement of said gripping element and handle in said different plane when predetermined forces are applied 20 tending to move said gripping element and handle relative to each other in said different plane. 25
